UNITED STATES PATENT OFFICE.

HENRY C. MILLER, OF MILWAUKEE, WISCONSIN.

LOOSE-LEAF BINDER.

Application filed February 23, 1924. Serial No. 694,681.

To all whom it may concern:

Be it known that I, HENRY C. MILLER, a citizen of the United States, and resident of Milwaukee, in the county of Milwaukee and State of Wisconsin, have invented certain new and useful Improvements in Loose-Leaf Binders; and I do hereby declare that the following is a full, clear, and exact description thereof.

- 10 This invention relates to loose leaf binders. Objects of this invention are to provide a loose leaf binder in which flexible posts are employed to join the upper and lower sections, in which the posts freely slide into 15 one of such sections, and in which means are provided whereby the posts may be most readily clamped to the receiving section and may be easily detached from the other section.
- 20 Further objects are to provide a loose leaf binder in which there are no projecting portions of the posts, in which a very quick adjustment may be effected, in which a key for operating the device is not required, and 25 in which the clamping means serves also as an aid in guiding the flexible posts or members into the receiving section.

Further objects are to provide a simple type of binder in which the upper and lower 30 sections may be made as unitary members without requiring the opening of either of such sections to effect adjustments, and in which a maximum of strength and extreme simplicity is attained.

- 35 An embodiment of the invention is shown in the accompanying drawings, in which:—

Figure 1 is a vertical sectional view through the binder such view corresponding to a section on the line 1—1 of Figure 2.

- 40 Figure 2 is a horizontal sectional view through the lower section shown in Figure 1.

Figure 3 is a transverse view on the line 3—3 of Figure 1.

- 45 For ease in description, the terms upper and lower sections will be employed although, obviously, the relation of parts may be reversed without departing from the spirit of this invention.

50 The upper section is composed of an upper channel member 1, and a lower channel member 2 joined by U-shaped end pieces 3, such end pieces being conveniently riveted in position with the arms of the end pieces 55 received in depressed portions of the sections 1 and 22, as shown in Figure 1. The lower

channel member is provided with a pair of apertures within which a pair of sleeves 4 are rigidly secured. These sleeves are provided with beveled or counter sunk upper 60 portions 5 adapted to receive the heads 6 of the screws, such screws being threaded into the uppermost portions of the flexible posts 7. If desired, slides 8 may be carried in suitable guides 9 secured to the upper side of 65 the upper section 1, and adapted to removably cover the apertures through such section provided for the screw head 6. It is understood, of course, that both the upper and the lower sections are covered by suitable material 10 to give a finished appearance to the binder, and, if desired the end members 3 (see Figure 2) may be provided with outer extensions 11 which receive the pintle pins 12 of the covers 13'. The lower section 70 is composed of a pair of channel members 13 and 14 held together by suitable rivets or other means and by the end members 3, as described in connection with the upper section. This lower section is provided with apertures 15 upon its upper side through which the flexible posts 7 freely 75 pass. Adjacent these apertures, the portions of the upper channel member 14 are upturned, as indicated at 16, to provide entering or guiding lips and, upon the inner side 80 of the posts, this upper channel member is depressed to provide a curved guiding portion 17 against which the flexible posts are adapted to bind when the locking mechanism hereinafter described functions. The lower channel member 13 is provided with upturned curved deflectors 18 adapted to aid in guiding the flexible posts inwardly 85 towards each other in the interior of the lower section. Transversely positioned cylindrical locking members or bars 19 and 20 are mounted within the lower section and upon the outer side of the posts 7. These members 19 and 20 also serve, due to their 90 curved shape, as guides for the posts. The member 19 has a rod 21 rigidly attached thereto. This rod extends freely into the member 20, as may be seen from Figure 2, and a spring 22 bears against the end of 95 the rod, the other end of the spring bearing against a bracket or arm 23 carried by the member 20, thus operatively interposing the spring 22 between the member 20, and the rod 21. This spring, therefore, tends to 100 force the members 19 and 20 apart. A second rod 24 is also rigidly secured to the 105

member 19 and passes freely through the member 20. The projecting end 25 of this rod is threaded and is received within an internally threaded sleeve 26 of an adjusting or clamping nut, such sleeve being provided with a second sleeve 27 adapted to retain the sleeve 26 within the lower casing and prevent its withdrawal. The nut is provided with a manipulating knob or portion 28 located exteriorly of the lower casing, and at the inner end bears against the member 20. Stop pins 29 may be provided to limit the outward motion of the members 19 and 20, such stop pins preferably constituting the rivets by which the end members 3 are secured to the channel members 13 and 14.

The inner ends of the flexible posts 7 have one end of the tension springs 30 attached thereto, the other ends of such springs being attached to the rods 21 and 24, as may be seen from Figure 2. This arrangement is preferable but, under certain conditions, it may be found expedient to provide a single spring connected at its ends to the two posts in an obvious manner, and, under other conditions, it may be found expedient to dispense wholly with the springs. It is to be noted from Figure 2 that the rods 21 and 22 are bowed outwardly to provide free operating space therebetween for the enclosed mechanism.

It is further to be understood that in place of the linked flexible post 7, wire cables, cord or leather or other similar members may be employed and also in place of the springs other resilient means may be used.

The operation of the apparatus is as follows:—When it is desired to loosen the binder, it is merely necessary to rotate the manipulating nut thus permitting the spring 29 to force the members 19 and 20 apart. This allows the upper section to be moved away from the lower section, the flexible posts sliding out from the lower section in a free and easy manner against the tension of the springs 30. After the desired sheet has been inserted or removed, the upper casing is pressed downwardly towards the lower casing and the manipulating screw is again tightened thus forcing the members 19 and 20 against the fixed portion of the post 7,—such members 19 and 20 binding between the posts and the lower channel member 13 of the lower section. This action forces the posts into binding engagement with the curved portions 17 of the upper channel member 14 of the lower section, and thus locks the posts in position.

It is obvious that the posts 7 may be provided with additional removable sections whereby such posts may be indefinitely extended.

It will thus be seen that a loose leaf binder has been provided which may be most readily adjusted and locked in position, which does not require a manipulating key, and which has no projecting post. 70

It will, further be seen that this loose leaf binder is of sturdy construction and is not likely to get out of order, and may be cheaply and readily manufactured.

Although the invention has been described in considerable detail, it is to be understood that the invention may be variously embodied and is, therefore, to be limited only as claimed. 75

I claim:

1. A loose leaf binder comprising an upper section and a hollow lower section, flexible members secured to said upper section and projecting freely into said lower section, a pair of clamping members positioned within said lower section and adapted to bind against said flexible members, a rod secured to one of said clamping members and projecting through the other of said members, and a nut threaded upon said rod and bearing against the last mentioned member. 80

2. A loose leaf binder comprising an upper section and a hollow lower section, flexible members secured to said upper section and projecting freely into said lower section, a pair of clamping members positioned within said lower section and adapted to bind against said flexible members, a rod secured to one of said clamping members and projecting through the other of said clamping members, a nut threaded upon said rod and bearing against the last mentioned clamping member, and a spring for forcing said clamping members out of binding engagement with said flexible members. 95

3. A loose leaf binder comprising an upper section and a hollow lower section, flexible members secured to said upper section and projecting freely into said lower section, a pair of clamping members positioned within said lower section and adapted to bind against said flexible members, a rod secured to one of said clamping members and projecting through the other of said clamping members, a nut threaded upon said rod and bearing against the last mentioned clamping member, a second rod secured to one of said clamping members, and a spring operatively interposed between said rod and the other of said clamping members. 110

4. A loose leaf binder comprising an upper section having a pair of counter sunk holes therethrough, a lower hollow section having a pair of apertures opening into the hollow interior and having deflector portions adjacent said apertures, a pair of flexible members extending through said apertures into the hollow section and guided by said deflector portion with the free ends of such 125

flexible members extending towards each other, screws detachably joining the other ends of said flexible members and the upper sections and seated within the countersunk holes in such upper section, a pair of locking members for binding said flexible members to said lower section in any one of an infinite number of positions of adjustment, and a screw for forcing said locking members into locking engagement with said flexible members.

5. A loose leaf binder comprising an upper section, a hollow lower section, a pair of flexible posts secured to said upper section and extending into said lower section with their free ends directed towards each other, a pair of cylindrical locking bars extending

transversely of and located within said hollow section adjacent each end and upon the outer side of said flexible posts and 20 adapted to guide said posts as they enter said hollow section, a rod secured to one of said bars and passing freely through the other of said bars, and a nut threaded upon said rod and bearing against said last mentioned bar, said nut having a manipulating knob located exteriorly of said hollow section.

In testimony that I claim the foregoing I have hereunto set my hand at Milwaukee, 25 in the county of Milwaukee and State of Wisconsin.

HENRY C. MILLER.
